UNITED STATES PATENT OFFICE

114,425

DESIGN FOR A REDINGOTE

George Constantine, Mattapan, Mass.

Application February 24, 1939, Serial No. 83,173

Term of patent 3½ years

To all whom it may concern:

Be it known that I, George Constantine, a citizen of the United States of America, residing in Mattapan, county of Suffolk and State of Massachusetts, have invented a new, original, and ornamental Design for a Redingote, of which the following is a specification, reference being had to the accompanying drawing, forming part thereof.

Fig. 1 is a front view of a redingote showing my new design.

Fig. 2 is a rear view thereof.

The characteristic feature of my design resides in the specific puffed embroidery down the front and around the neck portion of the redingote, as shown.

I claim:

The ornamental design for a redingote, substantially as shown and described.

GEORGE CONSTANTINE.
